[57] CLAIM

The ornamental design for a picture frame moulding, as shown and described.

DESCRIPTION

FIG. 1 is a front view of a moulding according to my invention;

FIG. 2 is a perspective view of the outer side face and top face of the moulding of FIG. 1;

FIG. 3 is a perspective view of the inner side face and back face of the moulding of FIG. 1; and

FIG. 4 is an end view of the moulding.

The moulding is shown broken away at the center in FIGS. 1-3 to indicate indeterminate length.
